UNITED STATES PATENT OFFICE.

CHARLES GRANT HARRIS, OF NILES, OHIO, ASSIGNOR TO THE HARRIS AUTOMATIC PRESS COMPANY, OF NILES, OHIO, A CORPORATION OF OHIO.

DAMPENER FOR SHEET FEEDS OR SEPARATORS.

No. 811,843.

Specification of Letters Patent.

Patented Feb. 6, 1906.

Application filed February 24, 1905. Serial No. 247,130.

To all whom it may concern:

Be it known that I, CHARLES GRANT HARRIS, of Niles, in the county of Trumbull and State of Ohio, have invented certain new and useful Improvements in Dampeners for Sheet Feeds or Separators; and I do hereby declare the following to be a full, clear, and exact description of the invention, such as will enable others skilled in the art to which it appertains to make and use the same.

In the feeding or separating of paper by bands, rollers, or pushers having rubber faces it is necessary in order to secure best results to frequently clean and dampen the surface engaging the stock. It is then possible to readily feed or separate stock of various degrees of thickness and texture; but after the effect of the cleaning and dampening has worn away the most careful adjustment is necessary to make such devices feed even one kind of stock. It has heretofore been sought to furnish the necessary moisture by means of dampeners composed of hollow perforated rollers covered with cloth through which water or water and glycerin would percolate. The objection to all such devices has been the inability to secure an even dampening of the surface of the stock-engaging element. With a hollow perforated roll of the character specified the fluid will when the feeder or separator is not in operation drip at the bottom side and when the machine is again started up will deposit an extra amount of water, so much so, in fact, that several sheets will be spoiled before the press can be properly started. If the quantity of water is cut down so as to overcome this trouble, sufficient percolation will not result to answer the requirements.

The object of my invention is to provide a dampener which when the machine is in operation will supply a sufficient amount of moisture to give to the whole surface of the paper-engaging element a slight moistening and yet which when the machine is not in operation will not ordinarily allow any greater amount of water to seep to the surface thereof than may be taken up by evaporation.

My invention comprehends the employment of an imperforate fluid-containing body of such density of composition that the fluid will gradually seep to the exterior surface in sufficient quantity to properly moisten a

paper-engaging element contacting therewith. The rate or quantity of the flow or seepage may be increased by admitting a supply of air to the interior of the body.

The invention will be hereinafter fully set forth, and particularly pointed out in the claims.

In the accompanying drawings, Figure 1 is a view in perspective, showing the application of my moistener to a sheet feed or separator. Fig. 2 is a longitudinal sectional view. Fig. 3 is a side view. Fig. 4 shows the device as used in feeding from the top of a pile. Fig. 5 shows the application of my invention to a different form of feeder or pusher.

Referring to the drawings Figs. 1 and 3, 1 designates the frictionally-retarded element, and 2 the intermittently positively-driven element of a sheet feed or separator of the type embraced by Letters Patent No. 651,307, issued to me June 5, 1900. As shown in the drawings, the intermittently-driven element is composed of a series of bands passed around rollers 3. In order to secure good results and keep the bands in perfect condition for engaging the stock, I locate immediately thereunder and in engagement therewith the dampener 4. This is shown in the form of a hollow roller-like body, mounted at its ends in brackets 5, wherein it is free to turn. This roller is not made with perforations, but is composed of a clay-like substance, preferably diatomaceous earth, solid at one end, while its filling end is preferably hermetically sealed by a stopper or valve 6. By constructing this roller of a clay-like substance and sealing the same against the admission of air the water contained therein will seep through the wall thereof only in sufficient quantity to properly moisten the engaging feeder element. In this way the latter is uniformly dampened, and this is true even if the feeder has been idle for several hours, there being no danger, in restarting, of the bands being unduly moistened at any point, since the seepage does not exceed that which is taken up by evaporation when the feeder is not taking off the surface moisture. Should it be desired to secure heavier dampening by a greater flow of water, it is only necessary to allow of the inlet of a small amount of air—say by slightly loosening or opening up the

valve or stopper. In this event the water will flow more freely, and when the machine is stopped it will drip from the bottom of the roller if allowed to stand any length of time, the seepage being in excess of that which can be taken up by evaporation from the exterior surface.

In Fig. 4 the functions of the two elements of the feeder are transposed, as in feeding from the top of a pile. In this arrangement the frictionally-retarded element is 2^a and the positively-driven element is 1^a, the dampener being shown in engagement therewith.

In Fig. 5 I have shown the application of my dampener 4^a to a rubbing or pushing element consisting of a rubber roller 7 on a finger 8. This is done to illustrate the fact that my invention is not limited in its application, since it may be used in connection with various forms of feeders or pushers intended to have frictional contact with paper, cards, &c.

I claim as my invention—

1. A moistening device for paper feeding or pushing elements, comprising an imperforate fluid-containing body from which the fluid will gradually seep to the outer surface sufficient to moisten a paper-engaging element.
2. A moistening device for paper feeding or pushing elements, comprising an imperforate fluid-containing body from which the fluid will seep to the outer surface in quan-

ity not exceeding that which may be taken up by evaporation.

3. A moistening device for paper feeding or pushing elements, comprising a fluid-containing body of such density of composition that the fluid will gradually seep to the outer surface thereof, and means for sealing such body as against the admission of air.

4. A moistening device for paper-feeding bands or rollers comprising a fluid-containing body of diatomaceous earth from which the fluid will be caused to seep to the outer surface in quantity not exceeding that which may be taken up by evaporation or by a paper-engaging element contacting therewith.

5. A moistening device for paper-feeding bands or rollers comprising a fluid-containing body of diatomaceous earth from which the fluid will be caused to seep to the outer surface in quantity not exceeding that which may be taken up by evaporation or by a paper-engaging element contacting therewith, and means for controlling the admission of air to such body to increase the flow therefrom.

In testimony whereof I have signed this specification in the presence of two subscribing witnesses.

CHARLES GRANT HARRIS.
